UNITED STATES PATENT OFFICE

RENÉ PORTE, OF LEVALLOIS PERRET, FRANCE, ASSIGNOR TO SOCIETE HARDOLL (ETABLISSEMENTS HARIVEAU & DOLIMIER, ET RENE PORTE & CIE. REUNIS), OF LEVALLOIS PERRET, FRANCE

AUTOMATIC GASOLINE FEEDING APPARATUS

Application filed June 10, 1925, Serial No. 36,174, and in France November 14, 1924.

My invention relates to improvements in automatic gasoline feeding apparatus comprising two measuring receptacles.

The said improvements are applicable to 5 the class of feeding devices wherein the element controlling the distribution consists of a double-acting piston which controls a suitable distributing element, for instance a cylindrical slide-valve or a cock, by means of 10 a reversing device.

My said invention has for its object to provide for a more reliable working of the said distributing element.

Since the said distributing element is a device 15 having fixed dimensions which is movable within a bored-out portion having a stated size, with a determined play, it may be subject to a slight gripping action which is due to traces of oxidation on the friction 20 parts. Since the only force of reaction upon the said distributing element is produced by the reversing spring, it is readily observed that in certain conditions the said spring will not have sufficient force to overcome the 25 resistance due to this slight oxidation.

My invention consists in the obtainment of a considerable force which is available for starting the operation of the said distributing element, which force is obtained, not 30 from the spring, but from the driving piston which is acted upon by the entire pressure of the liquid serving for the disengagement.

My said invention will be set forth herein-after with reference to the appended drawings wherein:

Fig. 1 is a sectional elevation of the gasoline feeding apparatus comprising my said improvements, and Fig. 2 a section on the line C—D of Fig. 1 the valve and piston being 40 omitted from the figure. Fig. 3 is an end view of the mechanism shown in Fig. 1 the cover of the casing containing said mechanism being removed.

With reference to the said figures, it will 45 be observed that the apparatus comprises a gasoline inlet 1 communicating with a chamber 2 which is in turn connected with the spaces 3 and 4 through which the liquids supplied under pressure to the said inlet may 50 proceed into the measuring receptacles 5, 6.

In the position of the distributing slide valve 7 shown in Figure 1, the liquid can only rise through the conduit 8 into the receptacle 5, and this will take place until the liquid raises the float 9 in such manner as to close 55 the upper orifice of the said receptacle. At this time the excess of pressure prevailing in the receptacle 5 will impel the piston 10 to the right, thus swinging the main reversing lever 11; this latter, through the medium of 60 the springs 12, will move a second lever 13 to the left, thus displacing the slide valve 7 in such manner that the receptacle 5, formerly in the filling stage, will now be emptied through the discharge conduit 14, whilst the 65 receptacle 6, formerly in the emptying stage, will now be filled through the conduit 4.

My said invention consists in the use of a third lever 15 pivoting on the axle 16 and actuated by the main reversing lever 11 during this movement, and which—by means of the studs 17 and 18—positively actuates the lever 13 should the latter, due to any slight gripping of the said slide valve, fail to respond to the traction of the spring 12 when the lever 11 occupies the position symmetrical to the one shown in Fig. 1, due to the action of the piston 10.

Should this take place, it is observed that there is added to the action of the spring 12, 70 the effort due to the stud 17 which will depend upon the position of the piston 10, thus taking advantage of all the force of the pressure which is exercised upon the said piston.

From the above it will be noted that I have 75 provided a volumetric meter which includes measuring chambers each having an air vent with means for closing the vent, and also means by which liquid is supplied to and discharged from the chambers. The supply and discharge of the liquid is controlled by a valve mechanism which includes in the present embodiment of the invention two valves mounted on the valve stem to which a swinging lever is connected for shifting the valves. 80 The apparatus also includes means for moving this valve mechanism which includes a spring in which power is stored through the pressure developing on the liquid after the chamber is filled, and this stored power is 85 90 95

utilized for shifting the valve mechanism. The apparatus also includes another means for shifting the valve which is positive in its character and this is brought about through the lever 15 which is moved when the piston is moved through the pressure developing on the liquid after the chamber is filled, and when this lever 15 is moved it engages the lever which is connected to the valve stem 10 and will positively move the valve mechanism. In the present embodiment of the invention this positive movement of the valve mechanism may only shift the valve a slight distance when the spring will take up and complete the movement of the valve mechanism.

It is obvious that the invention is not however limited to the specific embodiment disclosed but includes all suitable modifications of the same which are adapted for a like purpose.

Claims.

1. A volumetric meter including in combination, two measuring chambers of given capacity, each chamber having an air vent, means for closing the vent, means through which liquid is supplied to and discharged from said chambers, a valve mechanism for controlling the supply to and the discharge from said chambers, actuating means normally inactive for operating said valve mechanism, and means controlled by the pressure developing on the liquid after the chamber is filled for positively starting the movement of the valve mechanism and initiating the movement of said actuating means for operating the valve mechanism.

2. A volumetric meter including in combination, two measuring chambers of given capacity, each chamber having an air vent, means for closing the vent, means through which liquid is supplied to and discharged from said chambers, a valve mechanism for controlling the supply to and the discharge from said chambers, said valve mechanism including a pivotally supported arm connected to the valve, a lever mounted to swing about said pivot, a shiftable device controlled by the pressure developing on the liquid after the chamber is filled connected to the lower end of said lever, a spring connected to the upper end of said lever and to said arm and operating when the connection to the lever passes across the longitudinal center line of said arm for shifting the valve, and means actuated by said shiftable device for moving said arm and starting the movement of the valve.

3. A volumetric meter including in combination, two measuring chambers of given capacity, each chamber having an air vent, means for closing the vent, means through which liquid is supplied to and discharged from said chambers, a valve mechanism, for controlling the supply to and the

discharge from said chambers, said valve mechanism including a pivotally supported arm connected to the valve, a lever mounted to swing about said pivot, a shiftable device controlled by the pressure developing on the liquid connected to the lower end of said lever, a spring connected to the upper end of said lever and to said arm and operating when the connection to the lever passes across the longitudinal center line of said arm for shifting the valve, a pivotally supported lever having spaced studs for engaging said arm to start the movement of the valve, and means whereby said lever carrying the studs is moved by said shiftable device.

4. A volumetric meter including in combination, two measuring chambers of given capacity, each chamber having an air vent, means for closing the vent, means through which liquid is supplied to and discharged from said chambers, a valve mechanism for controlling the supply to and the discharge from said chambers including a valve, a pivoted lever connected at its lower end to the valve, a device movably controlled by the pressure developing on the liquid, a lever mounted to swing about the pivot for said arm connected to said device, a spring connected to the upper end of said lever and to said arm for actuating the valve when the upper end of the lever passes the longitudinal center line of said arm, and a member movable with said device and having spaced studs disposed on opposite sides of said arm for engaging the arm to start the movement of the valve.

5. A volumetric meter including in combination two measuring chambers of given capacity, each chamber having an air vent, means for closing the vent, means through which liquid is supplied to and discharged from said chambers, a valve mechanism for controlling the supply to and the discharge from said chambers, actuating means normally inactive for operating the valve mechanism, means for positively starting the movement of the valve mechanism, and a device actuated by the pressure developing on the liquid after the chamber is filled and the air vent closed for operating the means for positively starting the movement of the valve mechanism, said starting means for the valve mechanism initiating the movement of the actuating means for operating the valve mechanism.

In testimony whereof I have hereunto set my hand.

RENÉ PORTE.
